UNITED STATES PATENT OFFICE

122,905

DESIGN FOR A COMBINED ASHTRAY AND CIGARETTE REST

Benjamin W. Morse, Ossining, N. Y., and Claude
D. Curry, Newark, N. J.

Application December 28, 1939, Serial No. 89,178

Term of patent 3½ years

To all whom it may concern:

Be it known that we, Benjamin W. Morse and Claude D. Curry, citizens of the United States, respectively residing in Ossining, county of Westchester, and State of New York, and in Newark, county of Essex, and State of New Jersey, have invented a new, original, and ornamental Design for a Combined Ashtray and Cigarette Rest, of which the following is a specification, reference being had to the accompanying drawing, forming part thereof.

In said drawing, the figure is a perspective view of a combined ashtray and cigarette rest showing our new design. The dominant features of our design reside in the portions shown in solid lines.

We claim:

The ornamental design for a combined ashtray and cigarette rest, as shown and described.

BENJAMIN W. MORSE.
CLAUDE D. CURRY.
